UNITED STATES PATENT OFFICE.

JAMES O. WEST, OF NEW YORK, N. Y.

DESIGN FOR ORNAMENTATION OF BUCKLES.

Specification forming part of Design No. 5,478, dated January 16, 1872.

Specification describing a Design for a Suspender-Buckle, invented by JAMES O. WEST, of 364 Broadway, New York city, in the county and State of New York.

The accompanying photographic illustration represents my new design.

The invention consists in ornamenting the front or face of a buckle by the application thereto of square and compass, masonically ar-

ranged. The letter "G" is incidentally shown, but not included in the design.

What I claim as new is—

The design for the ornamentation of the face of the buckle, as shown.

JAMES O. WEST.
